UNITED STATES PATENT OFFICE.

GEORGE EWING NICHOLS, OF SIOUX FALLS, DAKOTA TERRITORY, AS-SIGNOR OF ONE-HALF TO EMMET J. BROWN, OF SAME PLACE.

SNOW-EXCAVATOR AND AUTOMATIC DUMPER.

SPECIFICATION forming part of Letters Patent No. 367,837, dated August 9, 1887.

Application filed April 18, 1887. Serial No. 235,340. (No model.)

To all whom it may concern:

Be it known that I, GEORGE EWING NICHOLS, a citizen of the United States, and a resident of Sioux Falls, in the county of Minnehaha, in the Territory of Dakota, have invented new and useful Improvements in Snow-Excavators, of which the following is a description.

The invention relates to the class of excavators which are employed in connection with a locomotive-engine for removing obstructive accumulations of snow from the track and road-bed of a railway; and it relates particularly to the class of excavators in which two snow-receptacles are placed side by side lengthwise of the trackway, and are so pivoted upon their supporting-frames as to discharge their contents laterally outside the track.

The invention consists, in general, of two cars connected together for operation, the front car being adapted to underrun and receive the mass of snow, and the rear car being provided with mechanism for clutching, and with a novel system of chains, wheels, and journals for retaining the snow and for applying the power by which it is dumped when the excavator has been withdrawn to a point suitable for its discharge; and it consists, in particular, of the various novel elements and combinations of elements, which will first be described in detail, and then distinctly claimed.

In the drawings, Figure 1 represents a side elevation of the snow excavating and dumping apparatus. Fig. 2 is a top plan view of the apparatus, a portion of the dumpers and of the subjacent bed-frame being broken away to show the bearings and connections of the chains by which the dumpers are tilted. Fig. 3 is a top plan view, drawn to an enlarged scale, of portions of both of the cars, portions being broken out of the excavator-car, as in Fig. 2. Fig. 4 is a rear view of the apparatus. Fig. 5 is a transverse section on the line $x-x$ of Fig. 2, the dumpers being in position for discharging. Fig. 6 is a detail showing in side elevation the front portion of the rear car.

As seen in the drawings, A is or may be an ordinary flat car, and B is the snow receiving and discharging car. The floor of this car or

sections, $b b'$, which are placed side by side upon the bed-frame f of the car, and which incline downwardly, as shown, from the rear to the front, the rear portion being preferably of the height of an ordinary flat car, while the opposite extremity is supported upon small wheels w , so that the floor is at this point but a short distance, preferably but a single inch, above the top of the track-rails. These floor-sections $b b'$, technically termed the "dumpers," are provided at their coincident edges with vertical partitions b^2 and b^3 , respectively, which are secured in position by any suitable means.

To the front end of the frame of the car B is attached a shoe or shovel, B', preferably composed of iron, provided with a facing of steel, and from the ends of which rise vertical cutters b^4 and b^5 , placed edgewise to the front, as seen. The shoe B' is provided upon the bottom, in rear of the steel facing, with a guard, b^6 , composed of a bar of half-round iron, to prevent contact of the shoe with the track-rails.

The post or standard A' is rotatably supported upon the flat car A, its lower extremity being loosely stepped in the bed-frame of the car, while at a point somewhat below its mid-height it is recessed to receive the loosely-en-circling holding-collar a , which is connected to the floor of the car by rods a' .

The arm A², provided at its outer extremity with the rake or slicer a², is pivotally connected to the standard at a suitable distance below the annular collar a .

A small cog-wheel, c, upon one of the axles 85 of the rear truck of the car A, engages a larger cog-wheel, C, mounted upon a shaft, C', the journals of which have bearing in supports c^1 c^2 , which are fixed upon the car. A clutch, c³, upon the shaft C' at the right of the cog-wheel 90 C, is adjustable by a lever, c⁴, a similar clutch, c⁵, at the left, being operated by a lever, c⁶.

The lifting-chain C², secured to and running upon the shaft C' and over a pulley, a³, near the top of the standard A', is connected at its 95 opposite end to the arm A².

The central outer portion of the discharging floor sections or dumpers $b b'$ is provided with a connecting cross-chain, C³, running in sheaves or pulleys c⁷ and c⁸, between which chain C³ is 100

attached to the cross-chain C^3 , and extending rearwardly at a right angle therewith, is connected for actuation to the shaft C' .

In operation the snow-receivers b and b' having been forced into the drift of snow, a large body of it is severed from the surrounding mass by the cutters b^1 and b^2 , and by the descent of the rake or slicer a^2 upon the arm A^2 . The apparatus being then run to the rearward, the clutch c^3 is at the same time thrown into engagement, winding the lifting-chain upon its shaft and elevating the arm A^2 and its rake above the plane of movement of the sections b and b' . The clutch c^3 being then thrown into engagement, the chain C^4 is wound upon the shaft, drawing downwardly and inwardly the outer portion of the sections b and b' and discharging the contents thereof.

A distance-chain, b^6 , (one or more,) is attached below the coincident edges of the sections b and b' , securing the sections together, and thereby limiting their outward movement in the act of dumping to a perpendicular plane. A ratchet and pawl (not shown) are provided in connection with the clutch c^3 to retain the sweep or arm A^2 in its elevated position.

Upon the front portion of the car A , or upon a fixed undivided rear portion of the front car, is a standard, D , provided with shaft d , which carries small gear-wheel d' , operated by hand-wheel d^2 , to actuate large gear-wheel d^3 , upon the shaft d^4 of which runs a chain corresponding to the chain C^4 , above described, and, like it, connected to a chain which actuates the pivoted dumping sections b and b' . This hand-wheel mechanism is designed more particularly for use in discharging gravel or earth.

It will be understood that when the snow-carrying car is to be loaded the clutch c^3 at the left is disengaged, permitting the arm A^2 to descend, so that the rake or cutter a^2 , which, to insure the requisite strength, is composed of steel, will bury itself in the snow.

The snow-receptacles being pivoted near their center transversely, but little power is required to tilt them and discharge their contents.

In Fig. 1 I have represented in dotted lines a short arm, which is provided with a pulley and with a strengthening-brace, and which may be used when it is desired to exert the lifting-power more directly.

When it is desired to use the rear car as a wrecking-car, a much shorter arm than that shown in full lines will be found most advantageous, and this will be pivoted to the standard A' at a point above, instead of below, the collar a .

When the excavator-car is unprovided with the hand-wheel mechanism, the dumping-sections will ordinarily extend the entire length of the car.

The attachment of the dumper-actuating chains to the under surface and outer edge of the dumping-sections, instead of to the upper surface and inner edge thereof, as in a former construction, is regarded as advantageous, in that the chains are unexposed to injury, and in that through their operation the sections may be tilted until they are brought to a perpendicular, or nearly perpendicular, position, and will thus more readily and certainly discharge their contents.

Having described my invention, I claim—

1. The snow receiving and discharging car B , consisting, essentially, of the bed-frame f , provided with bottom bearing-sheaves, as described, and the pivoted longitudinal floor-sections, in combination with the rear car, A , having shaft C' and the interconnecting chains C^2 and C^4 , substantially as shown and set forth.

2. The snow-receiving car or excavator B , embracing inclined frame, having sheaves, as set forth, and the coincident pivoted sections b and b' , each having a guard or partition at its inner edge only, in combination with the rear car, A , having cog-wheels c and C , standard A' , arm A^2 , and lifting-chain C^4 , substantially as described.

3. The combination, with the snow-receiving sections b and b' , provided, respectively, with the longitudinal guards b^2 and b^3 , of the wheels c and C , and the chains C^2 and C^4 , for the purposes described.

4. The combination of car B , having sections b and b' and shoe B' , with the car A , having the standard A' , the arm A^2 , provided with the rake a^2 , the wheels c and C , and the chains C^2 , C^3 , and C^4 , substantially as and for the purposes specified.

5. In a snow-excavating apparatus, the frame f , having the pivoted dumping-sections b and b' , provided, respectively, with partitions b^2 and b^3 , and the sheaves c^1 and c^2 , as described, in combination with a winding mechanism, and a chain or chains running in the sheaves beneath the bed-frame and connecting such winding mechanism with the outer edge and under surface of the dumping-sections, substantially as and for the purposes specified.

GEORGE EWING NICHOLS.
